UNITED STATES PATENT OFFICE.

JOHN LEVEY, OF CHICAGO, ILLINOIS, ASSIGNOR TO HERMAN ZITZWITZ,
OF CHICAGO, ILLINOIS.

AMMONIA-CONDENSER AND OIL-TRAP DEVICE.

No. 839,303.

Specification of Letters Patent.

Patented Dec. 25, 1906.

Application filed November 16, 1904. Serial No. 232,975.

To all whom it may concern:

Be it known that I, JOHN LEVEY, a citizen of the United States, residing at Chicago, in the county of Cook and State of Illinois, have invented a certain new and useful Improvement in Ammonia-Condensers and Oil-Trap Devices, of which the following is a specification.

My invention relates to ammonia-condensers and oil-traps, such as used in connection with refrigerating-machines.

It is illustrated in the accompanying drawings, wherein—

Figure 1 is a vertical section of the entire device, and Fig. 2 a bottom end view of it.

Like parts are indicated by the same letter in both figures.

A is an exterior cylinder having at its upper end firmly attached thereto the collar A' and at its lower end the bottom plate A². Secured upon the upper end of the cylinder and the collar A' is the top plate A³, with suitable packing A⁴. It is secured in any desired manner, as by bolts A⁵.

B is an inner cylinder secured to the coupling B', from which proceeds also the pipe B², which passes out through the packing gaskets B³ B⁴, secured in any desired manner. From the lower end of this pipe proceeds the discharge-pipe B⁵, controlled by the valve B⁶. The pipe B is received between downwardly depended centering-lugs A⁷ A⁷, formed on the inside of the top plate A³.

C is a short pipe which projects to any desired distance down inside the cylinder B and is preferably firmly secured, as at C', centrally in the top plate A³ and contains the valve C² to control its discharge-aperture, as the valve B⁶ controls the discharge-aperture of the pipe B⁵. The respective valve-stems are shown at B⁷ and C³.

D is a gage in the chamber D', formed by the lower part of the cylinder A.

E is one end of a pipe which passes through the bottom plate A², being packed by the packing-ring E'. This pipe extends up through the chamber D' and is coiled, as indicated, and emerges through the top plate A³, where it is again secured and packed by the packing-ring E² and opens into the discharge-pipe E³. E⁴ is a similar pipe with packing-rings E⁵ and E⁶. This pipe also passes up through the chamber D', is coiled, passes out

through the top plate and into the discharge-pipe E³.

In Fig. 1 the pipe-connecting parts associated with the bottom plate are removed. They are shown, however, in Fig. 2, where a cross-pipe F, controlled by the valves F' F², is shown. This cross-pipe is provided with connections F³ F⁴, which lead to the pipes E and E⁴.

G is a valve in the bottom of the chamber D'.

J J are bolts whereby the packing-rings E' and E⁵ are held in position, and the packing-rings E² and E⁶ are similar and they are similarly held.

I have not shown the means for supporting the device, as the same may be supported in any desired way.

It will be understood that these several devices are shown as in a sense diagrammatic and as intended to illustrate a single form of my invention. Obviously considerable departures could be made without departing from the spirit of my invention. The double coil, the arrangement of the coils, the arrangement of the pipes, connections, the dispositions of the several parts, as well as other features, could be greatly varied.

The use and operation of my invention will be evident. The cooling fluid may be run in at the bottom through the coils and it will pass out at the top. The ammonia and oil vapor will be run in through the pipe C. The oil-vapors being heavy will drop to the bottom of the inner cylinder B, separating from the ammonia-vapors at the bottom of the pipe C. The ammonia-vapors will pass upwardly, as indicated by the arrows, and down through or about the coils and will appear in a condensed form in the chamber D'. The oil will be drawn off through the valve B⁸ and the condensed ammonia through the valve G. As previously suggested, this operation could also be varied somewhat and would be by variations in the arrangement of the parts without departing from the spirit of my invention.

It should be pointed out that the arrangement of parts is such that the contraction and expansion has little or no tendency to disturb the joints. The inner case is connected at but one end. The ammonia-supply pipe is connected at but one end. The

cooling-coils are connected to both ends of the condenser, but between those ends is developed a long spiral coil in each case, which can thus take up contraction and expansion 5 without putting any considerable pressure on the connections. In short, the coils have a spring action to protect the joints.

In the ordinary operation of the machine it will be understood the ammonia-gas will 10 be sent into the separating-chamber under pressure from a compressor. (Not here shown.) The ammonia-vapors will be laden with oil and the separation of the oil from the ammonia will take place in this separating-chamber. The device, it will be seen, 15 consists of an inclosed shell which forms with the cooling-pipe coils a condensing-chamber in the top part and in the bottom a fluid-receiving chamber to receive the condensed 20 ammonia-gas. Inside of the shell is another chamber where the oil and ammonia are separated.

I claim—

1. In a condenser for refrigerating apparatus and the like, the combination of a closed shell, pipe-coils for a refrigerating agent in said shell, a separating-chamber within said shell and communicating therewith at the top, means for admitting the gas 25 into the separating-chamber and an oil-outlet 30 leading from the separating-chamber through

the shell, said separating-chamber having a slidable coupling with the top of the shell.

2. In a condenser for refrigerating apparatus and the like, the combination of a shell 35 closed at the top and bottom with a coil of pipes for a refrigerating agent within said shell, a separating-chamber contained wholly within said shell and opening into the same at the top of the said shell, means for slidably connecting the said chamber with the top of said shell, means for admitting the gas 40 into the separating-chamber, and an oil-outlet leading from the separating-chamber.

3. In a condenser for refrigerating apparatus and the like, the combination of a shell closed at the top and bottom with a coil of pipes for a refrigerating agent within said shell and a separating-chamber within said shell and opening into the same at the top, 45 an oil-outlet extending through the bottom of said closed shell, a connection between the separating-chamber and the top of said closed shell and a connection between the separating-chamber and the said oil-outlet, 50 one of said connections being a slidable connection.

JOHN LEVEY.
